CLAIM

The ornamental design for a pencil sharpener, as shown and described.

DESCRIPTION

FIG. 1 is a rear perspective view of a pencil sharpener showing my new design.

FIG. 2 is a front perspective view of FIG. 1.

FIG. 3 is a left side view of FIG. 1; the right side view is a mirror image of the left side view.

FIG. 4 is a front view of FIG. 1.

FIG. 5 is a rear view of FIG. 1; and,

FIG. 6 is a top view of FIG. 1.

The broken lines in the drawings are for the purpose of illustrating environment and form no part of the claimed design.
